PACKAGE OF COASTERS

Joseph L. Sholkin, Newton, Mass., assignor to Beacon Products Corporation, Boston, Mass., a corporation of Massachusetts

Application July 3, 1948, Serial No. 147,369

Term of patent 3½ years

(Cl. D58—11)

To all whom it may concern:

Be it known that I, Joseph L. Sholkin, a citizen of the United States, residing in Newton, in the county of Middlesex and State of Massachusetts, have invented a new, original, and ornamental Design for a Package of Coasters, of which the following is a specification, reference being had to the accompanying drawing forming a part thereof, in which:

The bottom of the container is plain.

I claim:

The ornamental design for a package of coasters, substantially as shown and described.
JOSEPH L. SHOLKIN.
